United States Patent Office

Des. 175,950
Patented Nov. 1, 1955

175,950

MICROPHONE

Bruce Kamp, Springfield, Pa., assignor to The Astatic Corporation, Conneaut, Ohio, a corporation of Ohio

Application May 13, 1955, Serial No. 35,969

Term of patent 7 years

(Cl. D26—14)

I claim:

The ornamental design for a microphone, as shown.
